Patented Apr. 15, 1919.

INVENTOR

Maurice Daniel Shatt

BY his ATTORNEY

Max. Ordman

UNITED STATES PATENT OFFICE.

MAURICE DANIEL SHATT, OF NEW YORK, N. Y.

DESIGN FOR A PEACE-FLAG.

53,210.

Specification for Design.

Patented Apr. 15, 1919.

Application filed January 28, 1919. Serial No. 273,655. Term of patent 3½ years.

To all whom it may concern:

Be it known that I, MAURICE DANIEL SHATT, a citizen of the United States, residing at New York, in the county of New York and State of New York, have invented a new, original, and ornamental Design for Peace-Flags, of which the following is a specification, reference being had to the accompanying drawing, forming part thereof.

The figure is a face view of the peace flag, showing my new design.

I claim:

The ornamental design for a peace flag as shown.

MAURICE DANIEL SHATT.

Witnesses:

C. G. P. KNIGHT,
MAX D. ORDMAN.
